United States Patent Office

Des. 180,849
Patented Aug. 20, 1957

180,849

TOY AUTOMOBILE

Johnny Spensieri, Toronto, Ontario, Canada

Application November 5, 1956, Serial No. 43,668

Term of patent 7 years

(Cl. D34—15)

Figure 1 is a perspective view of a toy automobile viewed from the front end and showing my new design; and

Figure 2 is a further perspective view of the toy automobile viewed from the rear end.

I claim:

The ornamental design for a toy automobile, as shown.
